MULTIPLE LEAD PENCIL

Hans Reusch, Pforzheim, Germany

Application May 18, 1938, Serial No. 208,572
In Germany June 10, 1937

9 Claims. (Cl. 120—14)

This invention relates to a multiple lead pencil in which lead holders are shiftably arranged in a pencil casing in such a manner that their shanks can move in guides inserted in the casing and carry knobs which project through slits in the casing.

The known pencils of this type are open to the objection that the casing slots are open along the greater part of their length, so that dust, dirt, rain drops and the like can penetrate into the casing, quite apart from the fact that the hollow space visible through the slots does not look nice.

These disadvantages are overcome according to the invention in that shank springs are arranged, one in each of the guides inserted in the casing, and presses the shank of the corresponding lead carriers against the inner side of the guide slot.

Five embodiments of the invention are illustrated by way of example in the accompanying drawing, in which:—

Fig. 1 shows a multiple lead pencil in elevation, Fig. 2 is a longitudinal section of Fig. 1,

Fig. 3 is a cross-section on line 3—3 of Fig. 2, Fig. 4 shows in front elevation a lead holder shank constituting the second form of construction,

Fig. 5 is a side elevation of Fig. 4, Fig. 6 shows a portion of the casing with slot for the lead holder shank illustrated in Figs. 4 and 5,

Fig. 7 shows in front elevation a modified construction of the lead holder shank constituting the third form of construction,

Fig. 8 is a side elevation of Fig. 7,

Fig. 9 shows a portion of the casing with slot for the lead holder shank illustrated in Figs. 7 and 8,

Fig. 10 shows in front elevation a portion of another construction of the lead holder shank, constituting the fourth form of construction,

Fig. 11 shows a portion of the casing with slot for the lead holder shank illustrated in Fig. 10, Fig. 12 is a cross-section through the pencil showing the guide for lead holder shanks and constituting the fifth form of construction.

On the back of the lead holder shank *a* of all forms of construction, a curved shank spring *b* is fixed which, as a slide spring, slides on and bears against the guide *d* fixed in the pencil casing *c* and presses the shank *a* against the inner side of the slot *e* formed in the casing *c* and thus closes this slot as tightly as possible.

In the first form of construction illustrated

in Figs. 1 to 3, the lead holders *a*₁ are locked in their extreme positions by two catch knobs *f* and *g* which are fixed directly on the outer side of each of the lead holder shanks *a*, the knob *f* being at the front end and the knob *g* at the rear end of the shank *a* which is approximately twice the length of the slot *e* and has a shifting knob *h* at about the middle of its length so that the shank closes the slot *e* on the rear side irrespectively of the position of the lead holder *a*₁. The front and rear edges *e*₁ and *e*₂ of the slot *e* serve as abutments for the catch knobs *f* and *g* in such a manner that the front knob *f* engages the front edge *e*₁ of the slot *e* when the lead holder *a*₁ is in retracted position and the rear catch knob *g* the rear edge *e*₂ of the slot when the lead holder *a*₁ is in writing position. No widened portion serving as notch is necessary in this form of construction. The disengagement of the catch knobs *f* and *g* is effected by pressure exerted by a finger on the knob *h* which finger at the same time shifts the lead holder *a*₁ against the action of its spring *b*. The catch knobs *f* and *g* engage behind the edges *e*₁ and *e*₂ automatically under the influence of the shank *a* spring *b*.

In the second form of construction illustrated in Figs. 4 to 6 one of the catch knobs *i* is at the rear end of the lead carrier shank *a* as in the first form of construction, whereas the second catch knob *k* projects laterally from the shifting knob *h* fixed about midway of the length of the shank *a*. The slot *e* has at its rear end a lateral widening *e*₃ serving as a notch. When the lead carrier *a*₁ is shifted into writing position, the catch knob *i* fixed on the rear end of its shank *a* engages this widened portion *e*₃. The knob *i* is disengaged and the lead holder *a*₁ retracted in the same manner as in the first form of construction. If the lead holder shank *a* is in its extreme rear position the catch knob *k* projecting laterally from the shifting knob *h* engages in the widened portion *e*₃. The arrangement of the catch knob *n* on the shifting knob *h* presents the advantage that its disengagement is effected more easily and reliably by exerting pressure on the shifting knob *h*.

This advantage is still more apparent in the third and fourth forms of construction illustrated in Figs. 7 to 9 and 10 and 11 respectively as only a single catch knob *m* or *n* is provided which projects laterally from the shifting knob *k*. This makes it necessary to form two lateral widenings or notches *e*₄, *e*₅ and *e*₆, *e*₇ respectively, arranged one at the front and the other at the

rear end of slot *e*. The catch knob *m* or *n* in its extreme forward position engages in the notch *e₅* or *e₇* and in its extreme rearward position in the notch *e₄* or *e₆*.

5. In the fourth form of construction the catch knob *n* projecting laterally from the shifting knob *h* (Fig. 10) is arranged in the middle of the shifting knob *h*. Consequently, it is located directly below the point on which the finger pressure is exerted and is consequently easily disengaged. If pressure is exerted on the shifting knob *h* for disengaging the catch knob *n* from one of the notches *e₆* or *e₇* (Fig. 11) the pressure, with this practical arrangement of the catch 10 knob *n* acts directly on this knob so that even a slight pressure is sufficient for effecting the disengagement. The effort necessary for depressing the shifting knob *h* with the finger is consequently less and the manipulation more convenient than in the other examples illustrated.

Any desired number of lead holders *a₁* can be provided in the multiple lead pencil. Thus the casing *c* may accommodate six lead holders as shown in Fig. 12 instead of four as shown in 25 Fig. 3.

I claim:

1. A multiple lead pencil, comprising in combination a pencil casing having a plurality of longitudinal slots, a plurality of guides in said 30 casing, a plurality of lead holders corresponding to the number of guides and accommodated in said casing, shanks one projecting from the rear end of each of said carriers into the corresponding guide, shifting knobs one projecting from 35 the outer side of each of said shanks through one of said slots for shifting said holders into and out of said casing, and springs one fixed on the inner side of each of said shanks and bearing against one of said guides to press said shanks 40 against the inner side of said casing at a corresponding slot.

2. In a multiple lead pencil as specified in claim 1, at least one catch knob on each of said shanks besides said shifting knob and adapted 45 to lock said shank in an extreme position under the action of the shank spring.

3. A multiple lead pencil as specified in claim

1, in which the lead holder shanks are approximately twice the length of the longitudinal slots and the shifting knobs are arranged approximately in the middle of the length of the shanks so that said shanks always close said slots on the inner side even in their two extreme positions. 5

4. In a multiple lead pencil as specified in claim 1, two catch knobs arranged one at the front end and the other at the rear end of each of said shanks and adapted to engage the front and rear 10 edges respectively of said longitudinal slots under the action of the shank springs to lock said shanks in forward and retracted positions.

5. A multiple lead pencil as specified in claim 1, each of said longitudinal slots having a lateral 15 widening at its rear end forming a notch, and each shank having a catch knob at its rear end and a second catch knob projecting laterally from its shifting knob, said catch knobs adapted to alternately engage said notch to lock said shank 20 in its forward and retracted positions respectively.

6. A multiple lead pencil as specified in claim 1, each of said longitudinal slots having two lateral widenings forming notches one at its front 25 end and the other near its rear end, and each shank having a catch knob projecting laterally from its shifting knob and adapted to alternately engage said notches to lock said shank in its forward and retracted positions respectively. 30

7. A multiple lead pencil as specified in claim 1, each of said longitudinal slots having two lateral widenings forming notches one near its front end and the other near its rear end, and each shank having a catch knob projecting laterally 35 from the middle and adapted to alternately engage said notches to lock said shank in its forward and retracted positions respectively.

8. A multiple lead pencil as specified in claim 1, in which the springs are each fixed at one end 40 to the inner side of one of the shanks and each slide in one of the guides.

9. A multiple lead pencil as specified in claim 1, in which more than four lead holders are accommodated with the shanks in the casing. 45
